FORGING PRESS

Florence C. Biggert, Jr., Pittsburgh, Pa., assignor
to United Engineering & Foundry Company,
Pittsburgh, Pa., a corporation of Pennsylvania

Application June 25, 1942, Serial No. 448,445

12 Claims. (Cl. 73—10)

This invention relates to forging presses, and more particularly to presses for forging hollow bodies such as projectile shells.

It is among the objects of this invention to provide a forging press which is rapid in operation, which is relatively simple in construction, which is highly efficient, and which can be quickly and easily altered for forging different types of blanks.

In accordance with this invention, a vertically movable holder for a billet is provided with a central vertical opening and normally is held in elevated position. A vertical punch is mounted below the billet holder with its upper end projecting into the opening therethrough. A vertically reciprocable pot die is carried by means by which it can be moved down around a billet on the holder to forge it into a blank around the stationary punch while pushing the holder down. When the die is raised the billet holder is elevated by means independent of the die to strip the forged blank from the punch. The die likewise may be provided with means for automatically ejecting the blank therefrom. There preferably are a plurality of punches and billet holders all carried by a rotatable turret that is indexed from station to station at one of which the die is located. After the turret is indexed to remove a blank from the forging station the punch is cooled by cooling liquid automatically applied to it. The punches preferably are slidable vertically in the turret so that they can be removed when desired by lowering them through the turret. For this reason they are supported at one station by a plate normally flush with the top of the turret support, but the plate rests on vertically reciprocable means which can be lowered to lower a punch resting on the plate. The plate deposits a lowered punch on a carriage which can be moved laterally to position another punch over the plate that is then raised to elevate the second punch into working position in the turret.

The preferred embodiment of this invention is illustrated in the accompanying drawings in which Fig. 1 is a plan view of my forging press with the billet-centering jaws removed; Fig. 2 is a vertical section taken on the line II—II of Fig. 1; Fig. 3 is a fragmentary vertical section at 90° to the section of Fig. 2; Fig. 4 is a plan view of billet-centering jaws; Figs. 5 and 6 are enlarged horizontal sections taken on the lines V—V and VI—VI, respectively, of Fig. 2; Fig. 7 is a side view of the punch-changing apparatus below the turret; Fig. 8 is an enlarged fragmentary vertical section taken on the line VIII—VIII of Fig. 1; Fig. 9 is a horizontal section taken on the line 55

IX—IX of Fig. 2; and Fig. 10 is a fragmentary vertical section similar to Fig. 2 but showing the press in the position its elements occupy at the conclusion of a forging stroke of the die, and showing a punch lowered from the turret.

Referring to Figs. 1, 2, and 6 of the drawings, a base member 1 is mounted on a suitable foundation and is provided with a vertical opening 2 in which the lower end of a center post 3 is rigidly mounted. Mounted on the base member at one side of the post is a casting 4 to the opposite sides of which the adjacent ends of a curved plate 5 are connected. This plate is supported with its upper surface horizontal and flush with the top of the casting. The plate and casting form a circular table that supports a turret 6 slidably mounted thereon for rotation around the post.

The turret is provided with a plurality, preferably four, vertical openings equally spaced around it. Slidably mounted in each of these openings is a metal punch 9 that projects upwardly from the turret with its headed lower end resting on a metal bearing block 10 slidably mounted in the lower end of the turret opening, as shown in Fig. 2. These blocks slide on the table when the turret is turned and they normally hold the punches rigidly in place in the turret.

The upper end of each punch projects up into a vertical opening 12 through a billet-holding member 13 supported on the upper ends of three vertical rods 14 that are slidable in vertical openings in the turret. As shown in Fig. 8, the lower ends of these rods normally are spaced a short distance above the turret table by latches 16 having inclined upper cam surfaces 18 that engage corresponding inclined surfaces at the upper ends of notches 19 formed in the sides of the rods. Each latch is slidable horizontally in a cylinder 20 on the turret and is pressed into the notch in the adjoining rod by means of a compression spring 21 encircling the latch. The movement of the latch into the notch causes the engaging cam surfaces to lift the rod slightly.

The center of the turret has a downwardly extending post-encircling hub 22 on which a ring 23 is keyed, as shown in Fig. 6. Encircling this ring and oscillatable thereon is another ring 24 provided with a radial recess in which a dog 25 is mounted on a pin 26 journaled in the opposite walls of the recess. This dog normally projects into one of the notches 27 with which the inner ring is provided and is held there by a spring 28 connected to the dog and the dog ring. To oscillate the dog ring in order to index the turret the dog pin 26 is pivotally connected to a link 30

that is pivoted at its opposite end in a block 31. This block is reciprocated at a tangent to the rings in a guide member 32 by means of a piston rod 33 projecting from a hydraulic cylinder 34. As soon as the piston rod starts to move, the dog starts moving in a curved path away from the straight path of travel of slide block 31. By the time the block reaches the end of its stroke the dog is moving nearly at right angles to the path of the block. Consequently, the movement of the dog around center post 3 slows down as it approaches the end of its forward stroke and thus the turret is automatically retarded toward the end of each indexing step without the use of special retarding equipment.

When the turret carries four punches the inner ring 23 is provided with four notches 27, thus causing each punch to be indexed to four successive stations. At one of the stations a punch is directly above casting 4 which serves as a support for the punch-supporting block 10 at rest at that point. The top of the casting is recessed and contains a hardened steel block 36 on which the punch-supporting block rests. The other four stations are for loading, unloading, and punch-changing as will be explained later.

To hold the turret motionless while operations are being performed at the various stations it is provided with four peripheral recesses 37 adapted to receive a stop member 38 that temporarily locks the turret against rotation. The drawings show the stop member mounted on the outer end of a piston rod 39 reciprocable radially of the turret by a hydraulic cylinder 40 connected to base member 1. At the end of each indexing step the stop member is projected into the opposite turret recess 37 and is retracted therefrom just before dog 25 starts to index the turret to the next station.

Spaced from center post 3 on the opposite side of casting 4 are two more laterally spaced posts 46 and 47 mounted in fixed position. Rigidly mounted on the upper ends of all three posts is a vertical hydraulic cylinder 48 the axis of which is in alignment with the axis of a punch resting on block 36. Reciprocable in this cylinder is a piston 49 the lower end of which projects from the bottom of the cylinder. To force the piston down, fluid pressure is supplied to the top of the cylinder through a conduit 51. The piston is raised by fluid pressure supplied to the lower portion of the cylinder through a lateral conduit 52 and acting upon a collar 53 and packing member 54 encircling the upper end of the piston.

The projecting lower end of the piston carries a head 56 the sides of which are provided with three shoes 57 for slidably engaging the flat surfaces of the three posts facing the block, as shown in Figs. 2 and 5. These shoes thus guide the head in a straight line when the piston is moved up and down. Rigidly connected to the bottom of the head is a die housing 58 provided with an upwardly extending recess in which a pot die 59 is mounted. The die shown is one designed for forging shells for projectiles, but other dies may be used for forging other products. The die housing is provided with recesses 60 encircling the die and connected by horizontal passages to flexible hoses 61 that are connected to a water circulating system (not shown) by which the die is cooled.

At the loading station, which immediately precedes the forging station, a hot billet 65 is deposited on a billet holder 13 between two jaws 66 that center it over the opening in the holder,

The jaws are hinged at one end to a bracket 67 projecting from the holder and are urged toward each other by springs 68 at their outer ends. As shown in Figs. 2 and 4, the jaws are shaped to form a funnel-like member that facilitates centering of the billet on the support. They also have upwardly and outwardly flaring wing portions 69 for a purpose about to be disclosed.

After a billet has been deposited on a billet holder, the turret is indexed to bring the billet directly under the die at the forging station. Fluid pressure is then admitted to the top of forging cylinder 48 and the die is thus moved down over the billet. The downwardly moving die housing 58 engages the wings on jaws 66 to spread the jaws apart and out of the way of the die. After the die has completely surrounded the billet the die housing engages the top of the underlying billet holder, and the downward pressure is sufficient to force latches 16 back out of the notches 19 in the adjoining rods 14.

This downward movement of the billet holder and its supporting rods is permitted because casting 4 below the punch is provided with three vertical openings for slidably receiving the rods. Slidably mounted in these openings and aligned openings in base member 1 are rods 71 that are biased upwardly by a cylinder 72 slidable on a stationary vertical piston 73 through which fluid under pressure is constantly supplied to the cylinder from a conduit 74. The force of the downwardly moving die overcomes this pressure and moves the billet holder downwardly against it until the die finally comes to rest in the position shown in Fig. 10 where it will be seen that the billet has been pierced by the punch and shaped by the die into a hollow blank. The die is then reversed, and the release of pressure upon the billet holder permits cylinder 72 to rise and force the billet holder upwardly to strip the blank from the punch. As soon as notches 19 in rods 14 reach latches 16 the latter are snapped into the notches by springs 21, thus causing the engaging cam surfaces to lift rods 14 above the lower rods 71 and the turret table.

In order to strip or eject the forged blank from the die 59 the top of the die is provided with a vertical opening that extends up through the die housing and into a transverse recess 76 extending across the bottom of head 56. Loosely mounted in the vertical opening is a cylindrical ejector 77 provided with a central peripheral recess into which horizontal rods 78 project. These rods, which are mounted in the die housing, retain the ejector in the housing but permit it to move vertically within predetermined limits. The ejector normally hangs down into the die as shown in Figs. 2 and 3, but when the die is lowered around the billet the latter pushes the ejector up as shown in Fig. 10. In this position the ejector projects up into recess 76 where it supports a cross bar 79 slidable vertically on guide rods 80, shown in Fig. 3. When the die is elevated after forging a billet, the projecting ends of the cross bar strike the lower ends of stop rods 81 depending from the lower end of cylinder 48. These rods stop the cross bar so that further upward travel of the die causes the bar to be pushed down in recess 76, as shown in Fig. 3. The bar therefore pushes the ejector down into the die and strips the forged blank from it. The blank drops down between jaws 66 and rests on the underlying holder 13 again.

The turret is then indexed to carry the forged

blank to the unloading station and to carry a hot billet on a holder 13 from the loading station into forging position beneath the die. At the same time the punch and billet holder that were at the unloading station are moved around to the punch-changing station. As soon as a punch leaves the forging station it is sprayed or flooded with a cooling liquid, such as water. As shown in Figs. 2 and 9, this may be done by rotatably mounting on the center post a cylindrical water jacket 86 divided into four chambers 87 each of which is connected by a conduit 88 to a different one of the billet holders 13. The jacket is made to rotate with the turret by connecting them by means of a rigid bar 89, as shown in Fig. 2. Each holder is provided with a lateral passage by which the water is conducted to the central opening 12 where the upper end of the punch is located. Water is supplied to chambers 87 through an axial passage 90 in the center post communicating at its upper end with three radial passages 91. The latter are so located that only the chambers connected to the two billet holders that have just left the forging station are supplied with water. The punches at the loading and forging stations receive no water.

To permit punches to be quickly changed when they become worn or a different blank is to be forged, the station opposite the die is designated the punch-changing station. At this location table plate 5 is provided with an opening directly below bearing block 10, but this opening normally is closed by a plate 93 (Figs. 2 and 6) so that the various blocks 10 can slide over it without dropping through. The plate is supported upon the upper end of a piston rod 94 projecting from a vertical hydraulic cylinder 95 below base member 1. The piston rod extends through a central opening 96 (Fig. 2) in a horizontal base plate 97 projecting from the side of a vertical plate 98 attached to base member 1, this opening being large enough to receive plate 93 when lowered. When plate 93 is lowered the punch resting on it descends through the turret until the bottom of block 10 is about flush with the top of base plate 97, as shown in Figs. 7 and 10. In this position upper and lower pairs of horizontal bracing and pushing members 99 engage opposite sides of the punch and block 10. These members are hinged on parallel horizontal axes to the side of a vertical plate 100 that is slidable horizontally in guide members 101 secured to vertical plate 98. To prevent members 99 from interfering with the descent of punch-supporting plate 93, a pair of vertical spreading members 102 are connected at their upper ends to plate 93. These members keep the hinged members 99 spread apart far enough to permit plate 93 to move down between them.

After a punch has been lowered into the position shown in Fig. 7 it is pushed to the left off plate 93 and onto base plate 97 by means of the pushing members 99 which are moved by vertical plate 100. Plate 100 is actuated by means of a fluid pressure mechanism 103 behind plate 98. As the punch is slid along the base plate another set of pushing members 104 also hinged to vertical plate 100 slide a replacement punch 105, previously deposited on the right-hand end of the base plate, over plate 93. The latter is elevated to lift the punch and to project it up through the opening above in the turret. The turret is then ready to be rotated again while the punch that was removed from it and deposited

on base plate 97 can be removed from the dotted line position in Fig. 7 by a crane.

It will be understood that the various fluid pressure mechanisms referred to herein are operated by suitable controls in a fluid pressure system not disclosed.

According to the provisions of the patent statutes, I have explained the principle and construction of my invention and have illustrated and described what I now consider to represent its best embodiment. However, I desire to have it understood that, within the scope of the appended claims, this invention may be practiced otherwise than as specifically illustrated and explained.

I claim:

1. A forging press comprising a rotatable turret, a plurality of laterally spaced punches projecting upwardly therefrom, a dog adapted to oscillate around the axis of the turret for indexing the turret to carry the punches from station to station, reciprocable means operatively connected to the dog for oscillating it, the path of travel of said dog being in a direction nearly perpendicular to the path of travel of said reciprocable means at the conclusion of each forward stroke whereby the rotation of the turret is automatically retarded toward the end of each indexing step, a vertically reciprocable pot die above the turret at one of said stations, and means for moving the die down around each successive punch at said one station.

2. A forging press comprising a rotatable turret, a plurality of laterally spaced punches projecting upwardly therefrom, a dog adapted to oscillate around the axis of the turret for indexing the turret to carry the punches from station to station, reciprocable means, a link pivotally connecting said reciprocable means to the dog to oscillate it, said link being disposed nearly perpendicular to the path of travel of said means at the end of each forward stroke whereby the rotation of the turret is automatically retarded toward the end of each indexing step, a vertically reciprocable pot die above the turret at one of said stations, and means for moving the die down around each successive punch at said one station.

3. A forging press comprising a rotatable turret provided with a plurality of laterally spaced vertical openings therethrough, an upwardly projecting punch slidably mounted in each of said openings, means for indexing the turret to move the punches from station to station, a vertically reciprocable pot die above the turret at one of said stations, means for moving the die down around each successive punch at said one station, and vertically reciprocable means at another of said stations normally supporting the punches in the turret openings and adapted to be lowered to lower a punch thereon away from the turret.

4. A forging press comprising a support, a turret rotatable thereon, a plurality of laterally spaced punches carried by the turret and slidably on said support, means for indexing the turret to move the punches from station to station, a vertically reciprocable pot die above the turret at one of said stations, means for moving the die down around each successive punch at said one station, said support being provided with a vertical opening at another station, a plate normally disposed in said opening for supporting each punch when it arrives at that station, and vertically reciprocable means supporting said plate and adapted to be lowered to

lower a punch on the plate down through the turret.

5. A forging press comprising a support, a turret rotatable thereon, a plurality of laterally spaced punches carried by the turret and slidable on said support, means for indexing the turret to move the punches from station to station, a vertically reciprocable pot die above the turret at one of said stations, means for moving the die down around each successive punch at said one station, said support being provided with a vertical opening at another station, a plate normally disposed in said opening for supporting each punch when it arrives at that station, vertically reciprocable means supporting said plate and adapted to be lowered to lower a punch on the plate down through the turret and said opening, and means for moving the punch laterally off said plate and for positioning another punch over said plate whereby it can be elevated into operative position in the turret.

6. A forging press comprising a rotatable turret, a plurality of laterally spaced punches projecting upwardly therefrom, a plurality of vertically movable billet holders each provided with a central vertical opening receiving the upper end of one of the punches, means for indexing the turret to carry the punches and billet holders from station to station, a vertically reciprocable pot die above the turret at one of said stations, means below the turret at said one station adapted to bias the billet holder at that station upwardly, and means for forcing the die down around the underlying billet to forge it into a blank around the punch below it while pushing the adjoining holder down, said biasing means forcing said holder upwardly again to strip the blank from the punch as the die is elevated.

7. A forging press comprising a rotatable turret, a plurality of laterally spaced punches projecting upwardly therefrom, a plurality of vertically movable billet holders each provided with a central vertical opening receiving the upper end of one of the punches, means for indexing the turret to carry the punches and billet holders from station to station, a vertically reciprocable pot die above the turret at one of said stations, a plurality of vertical rods supporting each of said holders and slidable vertically through the turret, means normally holding said rods in their upper position, upwardly biased means directly below said rods at said one station for resisting downward movement of those rods, and means for forcing the die down around the underlying billet to forge it into a blank around the punch below it while pushing the adjoining holder down against the resistance of said upwardly biased means which forces said rods and holder upwardly again to strip the blank from the punch as the die is elevated.

8. A forging press comprising a rotatable turret, a plurality of laterally spaced punches projecting upwardly therefrom, a plurality of vertically movable billet holders each provided with a central vertical opening receiving the upper end of one of the punches, means for indexing the turret to carry the punches and billet holders from station to station, a vertically reciprocable pot die above the turret at one of said stations, a plurality of vertical rods supporting each of said holders and slidable vertically through the turret, spring-pressed cams normally holding the lower ends of said rods above the lower surface of the turret, upwardly biased means directly below said rods at said one station for resisting

downward movement of those rods, and means for forcing the die down around the underlying billet to forge it into a blank around the punch below it while pushing the adjoining holder down against the resistance of said upwardly biased means which force said rods and holder upwardly again to strip the blank from the punch as the die is elevated.

9. A forging press comprising a rotatable turret, a plurality of laterally spaced punches projecting upwardly therefrom, a plurality of vertically movable billet holders each provided with a central vertical opening receiving the upper end of one of the punches, means for indexing the turret to carry the punches and billet holders from station to station, a vertically reciprocable pot die above the turret at one of said stations, means below the turret at said one station adapted to bias the billet holder at that station upwardly, means for forcing the die down around the underlying billet to forge it into a blank around the punch below it while pushing the adjoining holder down, said biasing means forcing said holder upwardly again to strip the blank from the punch as the die is elevated, and means for introducing cooling liquid into the punch-receiving opening of each successive billet holder after it leaves said one station.

10. A forging press comprising a rotatable turret, a plurality of laterally spaced punches projecting upwardly therefrom, a plurality of vertically movable billet holders each provided with a central vertical opening receiving the upper end of one of the punches, means for indexing the turret to carry the punches and billet holders from station to station, a vertically reciprocable pot die above the turret at one of said stations, means below the turret at said one station adapted to bias the billet holder at that station upwardly, means for forcing the die down around the underlying billet to forge it into a blank around the punch below it while pushing the adjoining holder down, said biasing means forcing said holder upwardly again to strip the blank from the punch as the die is elevated, a stationary center post for the turret provided with an axial passage terminating in a radial passage, means for supplying a cooling liquid to the axial passage, a jacket encircling the post and rotatable with the turret, said jacket being divided into a plurality of separate chambers each adapted to communicate in succession with said radial passage, and a conduit connecting the punch-receiving opening of each billet holder with a different one of said chambers.

11. A forging press comprising a vertically movable holder for a billet, means biasing the holder upwardly, said holder being provided with a central vertical opening, a vertical punch mounted below said holder with its upper end projecting into said opening, a pot die above said holder reciprocable vertically independently thereof, pivoted billet-engaging members for centering a billet on said holder and provided with portions adapted to be engaged by said die to move said members away from each other, and means for forcing the die down around the billet to separate said members and forge the billet into a blank around the punch while pushing said holder down, said biasing means forcing the holder upwardly again to strip the blank from the punch when the die is elevated.

12. A forging press comprising a rotatable turret, a plurality of laterally spaced punches projecting upwardly therefrom, a plurality of ver-

tically movable billet holders each provided with a central vertical opening receiving the upper end of one of the punches, means normally holding said billet holders in their upper position with their upper ends above the tops of the punches, means for indexing the turret to carry the punches and billet holders from station to station, a vertically reciprocable pot die above the

5 turret at one of said stations, means for forcing the die down around an underlying billet to forge it into a blank around the punch below it while pushing the adjoining holder down, and means below the turret for forcing said holder upwardly again to strip the blank from the punch when the die is elevated.

FLORENCE C. BIGGERT, JR.
